LOUIS LEHR, OF BRIGHTON HEIGHTS, NEW YORK, ASSIGNOR TO SIMON BRUNER, OF FAR ROCKAWAY, NEW YORK.

FINGER RING AND THE LIKE.

Application filed November 24, 1926. Serial No. 150,393.

This invention relates to the art of ornamenting metallic surfaces and particularly to surfaces of precious metals when employed as jewelry.

In the manufacture of ornaments such as rings, watch cases, lockets, brooches, bracelets, buckles, and the like, it is desirable to ornament the surfaces of the articles by engraving or stamping thereon fanciful designs or inscriptions. For example, the visible surface of a finger ring mount is usually curved or impressed in an ornamental and pleasing manner and it is an object of the present invention to further improve the appearance of an article of jewelry by not only providing the same with an engraved or stamped design but by adding to the beauty of the article by incorporating in the design a combination of metals of different colors thus enhancing the appearance in a desirable and pleasing manner.

A further object of the invention is to provide a method of effecting the above result in a simple, economic and efficient manner.

In accordance with the present invention the surface of a metallic body, such as white gold, may be provided with an insert of yellow or green gold, the whole surface being given a harmonious design either by stamping or engraving so that when finished the resultant surface will appear as if made of a single body with a flush surface and at the same time include a plurality of different colored metals.

The invention does not, however, lie entirely in the new and useful article produced but in the method of its production whereby the applied contrasting metallic insert is united and made integral with the body to be ornamented in such manner that all visible indications as to the mode of union or line of demarcation between the differently colored metals is removed.

Furthermore, the invention is applicable to what is termed novelty jewelry which must not only be desirable from an artistic standpoint but must be producible at a cost commensurate with the purchasing range of the average person. The present method makes it possible to produce an article of jewelry of the character above set forth at a relatively low cost.

The invention will be more clearly under-

stood by reference to the accompanying drawing in which,

Fig. 1 is a side view of a finger ring having an insert of another material applied thereto in accordance with the present invention.

Fig. 2 shows two fillers or inserts to be applied to the ring shown in Fig. 1.

Fig. 3 shows a ring partly broken away to show inserted material.

Fig. 4 is a sectional view of a piece of metal having an insert in position to be pressed into interlocking engagement with the edges of a pocket or recess, and

Fig. 5 is a view similar to Fig. 4 but showing the insert in position after pressure has been applied thereto.

Although the method is applicable for the ornamentation of any metallic surface a practical embodiment of the same is shown in connection with a mount 10 of a finger ring 11. The mount may be inscribed with a fanciful design 12 and with pockets or recesses 13 and 14 of any suitable configuration. The perimeters of the recesses are undercut at 15 to provide projecting edges 16 as shown in Fig. 4. If the ring or mount is of white gold for example, then insert or filler pieces 17 and 18 of say yellow gold may be applied to the respective recesses in which they fit. Initially the fillers are of such dimensions as to closely fit between the edges. That is to say the edges of the fillers just clear the edges of the cavities or recesses. The fillers are of a thickness of substantially the same dimensions as the depth of the recesses.

The fillers may be temporarily held in position by any suitable form of union as by soldering or welding or even by an adhesive cement preparatory to a further operation which binds them in place. This operation consists in applying a pressure member as a suitable die (not shown) of the proper configuration to press the fillers into the cavities. Sufficient pressure is exerted so that the insert is peened or expanded to bring the edges thereof into interlocking engagement with the overhanging edges of the recesses.

After the application of pressure to the insert it takes the form of the recess and as shown in Fig. 4 presents a surface flush with that of the mount. The insert or filler may

be left blank and may be polished or engraved as with a special design or initial, or the insert piece may be in the form of a filigree, that is it may have apertures of a fanciful design so that when the insert is in place the color of the underlying metal will show, thus multiplying the contrasting effect.

It has been found preferable, however, to 10 decorate the insert at the same time the pressure is applied to force the same into bonded relation with the mount. The pressure member or die employed for this purpose may therefore be provided with the required design which is impressed upon the 15 insert simultaneously with the operation which works the metal into interlocking engagement with the edges of the recesses.

The design applied may be so arranged as 20 to completely eliminate any seam or line of division that might appear between the two metals.

It will be obvious that any number of inserts may be employed and by using two as 25 shown separated by a strip of the body metal, such strip may be ornamented to give the effect that the inserted metal is in one piece and bridged by the body metal.

Various other novel combinations may be 30 produced and it is to be understood that many modifications may be made which fall within the spirit and scope of the invention as set forth in the appended claims.

What is claimed is:

35 1. An ornamental article comprising a body portion having a cavity, a metallic insert in said cavity, said cavity having a depth substantially the same as the thickness of said insert and a fanciful design on said 40 body to ornament the same and conceal the line of demarcation between said body and said insert.

2. An ornamental article comprising a body of metal having a cavity, a metallic insert expanded in said cavity, and a fanciful design applied to the perimeter of the cavity to efface the line of demarcation between the two metals. 45

3. An ornamental article comprising a metallic body having a cavity therein and a 50 filler of substantially the same volume as said cavity so as to fill the cavity and be retained therein by the edges thereof the surface of said body being so ornamented as to conceal the line of demarcation between said body and said filler. 55

4. An ornamental article comprising a metallic body having a cavity of fanciful design, the bottom of the cavity being of greater area than the mouth thereof, and a metallic insert in said cavity, one side of said insert being in contact with the bottom of the cavity, the surface of the opposite side of said insert being flush with the surface of said body and a fanciful design upon 60 the surface of said body to conceal the line of demarcation between said insert and said body. 65

5. An ornamental article comprising a metallic body having a cavity of fanciful 70 design, the bottom of said cavity having a greater area than the mouth thereof and a metallic filler occupying said cavity one surface of said filler being in contact with the bottom of said cavity, the opposite surface of said filler being equal in area to the mouth of said cavity and flush with the surface of said body and a fanciful design upon 75 the surface of said body to conceal the line of demarcation between said filler and said body. 80

In testimony whereof I affix my signature.

LOUIS LEHR.
